United States Patent Office

Des. 202,252
Patented Sept. 7, 1965

202,252

TIRE

Loren G. Rahn, Allen Park, Mich., assignor to The B. F. Goodrich Company, New York, N.Y., a corporation of New York

Filed June 25, 1964, Ser. No. 80,579

Term of patent 14 years

(Cl. D90—20)

Fig. 1.

FIG. 2

FIG. 1 is a perspective view of a tire showing my new design; and

FIG. 2 is a transverse cross sectional view thereof.

The dominant features of the design reside in those portions shown in full lines.

I claim:

The ornamental design for a tire, substantially as shown and described.
